ROBERT L. MYERS, OF SAN DIEGO, CALIFORNIA

CIRCULATION CONTROL APPARATUS FOR THE LOW PRESSURE SIDE OF
REFRIGERATING SYSTEMS

Application filed October 21, 1927. Serial No. 227,675.

My invention relates to refrigerating systems and particularly to the chilling unit apparatus of refrigerating systems, and the objects of my invention are: first, to provide 5 an apparatus of this class in which the refrigerant is admitted from the high pressure to the low pressure side through a needle valve and diverges by a flexible partition to a chilling unit and returns to the other side 10 of said flexible partition which contains a float ball which governs the amount of refrigerant passing through the needle valve in said first partition; second, to provide an apparatus of this class in which the amount of 15 refrigerant in the entire refrigerating system may vary considerably without interfering with the operation of the chilling unit; third, to provide an apparatus of this class which prevents the ungasified refrigerant 20 from passing back to the compressor; fourth, to provide an apparatus of this class in which the valve housing and needle valve may be located in any position relative to the chilling coil; fifth, to provide an apparatus of 25 this class in which the valve housing is capable of absorbing heat from the surrounding air for gasifying the surplus of liquid refrigerant; sixth, to provide an apparatus of this class in which the output of the compressor 30 may vary considerably without interfering with the action of the chilling unit; seventh, to provide a needle valve and float housing of this class which is readily adaptable for any type of mechanical refrigerating 35 system; eighth, to provide a refrigerating apparatus of this class in which a plurality of chilling units together with the needle valve and float housing may be connected in multiple to a single compressing plant there- 40 by permitting independent operation of the several chilling units and to provide self adjustable means whereby a limited number of the chilling units may be disconnected without materially affecting the remaining 45 system; ninth, to provide an apparatus of this class which is especially adapted for apartment houses or the like where a plurality of small refrigerating units may be operated by a single compressing power 50 plant, and tenth, to provide an apparatus

of this class which is easily installed and repaired, durable, efficient in its action, sturdy of construction and which will not readily deteriorate or get out of order.

With these and other objects in view as 55 will appear hereinafter, my invention consists of certain novel features of construction, combination and arrangement of parts and portions as will be hereinafter described in detail and particularly set forth in the 60 appended claims, reference being had to the accompanying drawings and to the characters of reference thereon which form a part of this application, in which:

Figure 1 is a side elevational view of a 65 single chilling unit of my refrigerating system; Fig. 2 is an enlarged sectional view of the float and needle valve housing with parts and portions shown in elevation to facilitate the illustration; Fig. 3 is a transverse sec- 70 tional view thereof through 3—3 of Fig. 2 with parts and portions shown in elevation to facilitate the illustration; Fig. 4 is another transverse sectional view through 4—4 of Fig. 2; Fig. 5 is an enlarged elevational view 75 of the needle valve and diaphragm; Figs. 6, 7 and 8 disclose a slight modification of which Fig. 6 is a longitudinal sectional view thereof with parts and portions shown in elevation to facilitate the illustration; Fig. 80 7 is a transverse sectional view thereof through 7—7 of Fig. 6 and Fig. 8 is an enlarged elevational view of the needle valve and diaphragm with a portion thereof broken away and in section to facilitate the illustration, and Fig. 9 is a diagrammatical view 85 showing several chilling units connected in multiple and operated by a single compressor.

Similar characters of reference refer to 90 similar parts and portions throughout the several views of the drawings.

In the preferred form the needle valve housing 1, end plate 2, diaphragm 3, needle valve 4, support 5, pin 6, needle valve actuating means 7, link member 8, float 9, float chamber 10, and in the modification needle valve housing 11, end plate 12, diaphragm 13, needle valve 14, supporting means 15, pin 16, needle valve actuating means 17, link 100

member 18, float 19 and float chamber 20 constitute the principal parts and portions of my refrigerating chilling unit.

The needle valve housing 1 is provided with an axial positioned opening which extends the length of the housing. The extended end of the housing 1 is adapted to receive the end of a high pressure pipe H from a compressor unit, not shown. The passage 1a adjacent to the end of the high pressure pipe H is constricted and verges into a slightly larger passage 1b. The portion between the two passages 1a and 1b form a needle valve seat 1c. The passage 1b is widened forming a small chamber 1d which extends the remaining portion of the valve housing 1. The supported end of needle valve housing 1 is provided with an annular flange 1e through which bolts 1f extend which secures the needle valve housing to a plate 2. The plate 2 is secured by bolts 2d to the open end of the float housing to be described later. A passage 1g intersects the chamber 1d and is adapted to receive the one end C1 of a chilling coil C, as shown in Figs. 1, 2 and 3 of the drawings. The plate 2 is provided with an annular depression 2a with a concentric opening 2b therein which is centered on the axial line of the needle valve housing 1. Centered in the annular depression 2a and supported by its edges in a gasket positioned between the plate and the needle valve housing is a diaphragm 3. The diaphragm 3 is provided with several concentric corrugations therein to give added flexibility. Centered in the diaphragm 3, secured intermediate its ends therewith and forming fluid tight joint is a needle valve 4. The one of the two extended portions of the needle valve 4 is provided with a pointed end which extends into the passage 1b of the needle valve housing and is adapted to rest against the valve seat 1c when in a closed position. The needle valve adjacent to its pointed end is provided with a plurality of flat surfaces 4a which permits the refrigerant from the compressor to seep past the needle valve into the chamber 1d. The other extended portion of the needle valve passes through hole 2e in the end plate 2. The plate 2 is provided in its lower portion with an opening which receives a fitting 2b for receiving the low pressure end C2 of the chilling coil C. Directly above the fitting 2b another fitting 2c to which is secured a pipe L leading to the lower side of the compressor, not shown. Mounted on the inner face of the plate 2 is a support 5 which is provided with spaced apart lugs 5a. Pivotal mounted between the lugs 5a by means of a pin 6 is a needle valve actuating means 7 which is provided with an upwardly extending arm 7b which engages a slot 4b in the under side of the needle valve 4. Thus a pivotal movement of the needle valve actuating means 7 causes a reciprocal movement of

the needle valve 4. The actuating means 7 is connected by means of a link member 8 to a float 9. The float chamber 10 encloses the needle valve actuating mechanism. The float chamber 10 is provided with semi-spherical upper and lower portions connected by straight sides, as shown best in Fig. 4 of the drawings, and is closed at its one end. Its open end is provided with an annular collar to which is secured the end plate 2 by means of bolts 2d. The sides of the float housing 10 are provided with a plurality of spaced apart outwardly and vertically extending fins 10b, as shown in Figs. 1 and 4 of the drawings. Its closed end 10a is provided with similar vertical fins 10c.

In the modification the needle valve housing 11 is provided with an axial positioned opening extending therethrough. The extended end of the valve housing 11 is adapted to receive the high pressure pipe H from the condenser, not shown. The portion 11a of the axially extending passage is constricted and extends between the high pressure pipe H and the needle valve seat 11b. The remaining portion 11c of the opening is increased in diameter to receive a needle valve 14. The supported end of the needle valve housing 11 is provided with an annular flange 11d and is secured to an end plate 12 by means of bolts 11e. The end plate 12 is provided with a hollow cylindrical extended portion 12a which is concentric with the axial opening in the needle valve housing 11 and which is partially closed at its extended end having a small passage for receiving the portion of the needle valve 14. Secured between the end plate 12 and the valve housing 11 by means of an annular flange 13b is a cylindrical diaphragm 13. A cylindrical portion of the diaphragm 13 extends into the cylindrical portion 12a of the end plate 12, is closed at its extended end and is provided with annular corrugations 13c. Centrally mounted in the closed extended end portion of the diaphragm 13 is a needle valve 14. The needle valve 14 is secured intermediate its ends and makes a fluid tight joint with said diaphragm 13. The one end portion 14a of the needle valve is pointed and is adapted to engage the valve seat 11b when in its closed position. A chamber 13d is formed within the cylindrical portion of the diaphragm 13 and is bounded on one side by the central portion of the supported side of the valve housing 11. A passage 11f in the needle valve housing communicates with said chamber 13d and is adapted to receive a fitting which connects it in the low pressure side C1 of the chilling coil C, not shown. The lower portion of the end plate 12 is provided with a hollow fitting 12b to which is connected the low pressure side C2 of the chilling coil. Diametrically opposite the fitting 12b is a similar fitting 12c which communicates with

the low pressure side L of the compressor, not shown. A support 15 is provided which is secured to the end of plate 12 and is provided with a pair of spaced apart lugs 15a which 5 are positioned directly under that portion of the needle valve 14 which extends through the end plate 12. Mounted between the lugs 15a by means of a pin 16 is a valve actuating means 17 which is provided with an arm 17a 10 which engages a slot 14b in the under side of the needle valve 14, as shown best in Figs. 6 and 7 of the drawings. The needle valve actuating means 17 is connected by means of a link member 18 to a float 19. The means for 15 actuating the needle valve described in the modification is similar to that described in the preferred form of construction. The float housing 20 covers the needle valve actuating mechanism and is secured to the end plate 12 20 by means of an annular collar 20a. The float housing 20 is cylindrical in cross section and permanently closed at its one end by an end member 20b.

It will be noted that the float housings 10 25 and 20 may be interchanged without departing from the spirit of the invention.

The operation of my chilling refrigerating unit is as follows:

The compressed refrigerant which is in the 30 form of a liquid comes from the compressor through the high pressure pipe H and is expanded by means of the needle valve 4 or 14 into the chamber 1a or 13d. The expanded refrigerant passes through the refrigerating coil C, which may be of any form of construction, where a relatively large portion of the refrigerant evaporates to a gas. The gas and the remaining liquid refrigerant passes from the chilling coil into the float housing 40 where the gas passes out through the passage L to the compressing unit. The liquid which has not evaporated while passing through the chilling coil causes the float to fluctuate, thus controlling the amount of fluid passing 45 through the needle valve. When the liquid refrigerant rises too high in the float housing, the needle valve is closed until the required amount of refrigerant has evaporated. Thus no liquid will pass back to the 50 compressor.

It will be noted that the float and needle valve mechanism will permit a considerable fluctuation in the volume of refrigerant and that each unit when connected in multiple as 55 shown diagrammatically in Fig. 9 will work independent of each other, thus one of the units as shown in Fig. 9 may be disconnected without effecting the remaining units.

It is obvious from the construction as illustrated in the drawings and described in the foregoing specification that there is provided a refrigerating unit as aimed at and set forth in the objects of the invention and though I have shown and described a particular construction, combination and arrangement of

parts and portions I do not wish to be limited to this particular construction, combination and arrangement but desire to include in the scope of my invention the construction, combination and arrangement substantially as set 70 forth in the appended claims.

Having thus described my invention, what I claim as new and desire to secure by Letters Patent is:

1. In a refrigerating apparatus of the class 75 described, a chamber provided with an inlet and an outlet, a second chamber provided with an inlet and an outlet, said outlet of said first mentioned chamber communicating directly with said inlet in said second mentioned 80 chamber at the lower side thereof through a refrigerating coil whereby liquid refrigerant is delivered to said second mentioned chamber at the lower side thereof, a flexible partition between said first and second mentioned chambers, a needle valve secured and supported intermediate its ends in said partition for regulating the size of said inlet opening in said first mentioned chamber, and a float mounted in said second mentioned 85 chamber for actuating said needle valve.

2. In a refrigerating apparatus, a chilling unit comprising a valve housing, a float housing and a chilling coil and liquid refrigerant conductor communicating from said valve 90 housing to the lower side of said float housing, a flexible diaphragm positioned between said valve and float housings, and a needle valve secured and supported intermediate its 95 ends in said diaphragm for regulating the size of an inlet opening in said valve housing, said needle valve controlled by float means mounted in said float housing.

3. In a refrigerating apparatus, a chilling unit comprising a valve housing, a float housing and a chilling coil and liquid refrigerant conductor communicating directly from said valve housing to the lower side of said float housing, a substantially flat flexible diaphragm provided with corrugations therein, and a needle valve secured intermediate its 100 ends in said diaphragm for regulating the size of an inlet opening in said valve housing, said needle valve controlled by float 105 means mounted in said float housing.

4. In a refrigerating apparatus consisting of a compressor and condensing means, a plurality of chilling units mounted in multiple between said intake and said exhaust of 110 said compressor means, each of said chilling units comprising a valve housing, a float housing and a chilling coil and liquid refrigerant conductor communicating from said valve housing to the lower side only of said 115 float housing, a flexible diaphragm positioned between said valve and float housings, and a needle valve secured and supported intermediate its ends in said diaphragm for regulating the size of an inlet opening in said 120 float housing.

valve housing, said needle valve controlled by float means mounted in said float housing.

5. In a refrigerating apparatus, a chilling unit comprising a valve housing, a float housing and a chilling coil communicating from said valve housing to said float housing, a flexible diaphragm positioned between said valve and float housings, a needle valve secured intermediate its ends in said dia-
10 phragm for regulating the size of an inlet opening in said valve housing, said needle valve controlled by float means mounted in said float valve housing, said float means actuated by the unevaporated refrigerant from said chilling coil and fins extending from the side of said float valve housing for conducting heat to said unevaporated refrigerants in said float valve housing.

6. In a refrigerating apparatus, a chilling unit comprising a valve housing, a float housing and a chilling coil communicating from said valve housing to said float housing, a substantially flat flexible diaphragm provided with corrugations therein, a needle valve secured intermediate its ends in said dia-
20 phragm for regulating the size of an inlet opening in said valve housing, said needle valve controlled by float means mounted in said float valve housing, said float means actuated by the unevaporated refrigerant from said chilling coil and fins extending from the side of said float valve housing for conducting heat to said unevaporated refrigerants in said float valve housing.

7. A refrigerating apparatus consisting of a compressor and condensing means, a plurality of chilling units mounted in multiple between said intake and said exhaust of said compressor means, each of said chilling units comprising a valve housing, a float housing and a chilling coil communicating from said valve housing to said float housing, a flexible diaphragm positioned between said valve and float housings, a needle valve secured intermediate its ends in said diaphragm for regulating the size of an inlet opening in said valve housing, said needle valve controlled by float means mounted in said float housing, said float means actuated by the unevaporated refrigerant from said chilling coil conducted to the lower side of said float housing and fins extending from the side of said float housing for conducting heat to said unevaporated refrigerants in said float housing.

8. A refrigerating apparatus consisting of a compressor and a condensing means, a plurality of chilling units mounted in multiple between said intake and said exhaust of said compressor means, each of said chilling units comprising a valve housing, a float housing and a chilling coil communicating from said valve housing to said float housing at the lower side thereof, a substantially flat flexible diaphragm provided with corrugations therein, a needle valve secured intermediate

its ends in said diaphragm for regulating the size of an inlet opening in said valve housing, said needle valve controlled by float means mounted in said float housing, said float means actuated by the unevaporated refrigerant from said chilling coil and fins extending from the side of said float housing for conducting heat to said unevaporated refrigerants in said float housing.

In testimony whereof, I have hereunto set my hand at San Diego, California, this 14th day of October, 1927.

ROBERT L. MYERS.
